Des. 233,608

Patented Nov. 12, 1974

233,608

NUMERIC INPUT/AUDIO OUTPUT MULTIFUNCTION CONSOLE OR THE LIKE

Ronald I. Conway, Port Ewen, Robert V. Jones, Kingston, John J. Natoli, Woodstock, and John V. Stram, Poughkeepsie, N.Y., assignors to International Business Machines Corporation, Armonk, N.Y.

Filed July 16, 1973, Ser. No. 379,880

Term of patent 14 years

Int. Cl. D14—02

U.S. Cl. D26—5 C

FIG. 1

FIG. 2

FIG. 1 is a front, left side and top perspective view of a numeric input/audio output multifunction console or the like, showing our design.

FIG. 2 is a rear, right side and top perspective view thereof, the bottom being plain and unornamented.

We claim:

The ornamental design for a numeric input/audio output multifunction console or the like, substantially as shown and described.
